PROJECTILE PROPELLED INJECTOR

Walter H. Tinker, Glenside, Pa., assignor, by
mesne assignments, to H S B Corporation, a cor-
poration of Pennsylvania

Application August 12, 1944, Serial No. 549,221

8 Claims. (Cl. 103—234)

This invention relates to a fluid pressure pump for pumping liquid, and has for its general object to provide a pump operating according to the projectile principle, in which a mass of water confined as a free piston within a conduit is subjected to the variable force of expanding fluid under pressure, whereby it is driven through the conduit with accelerated velocity, and into a pressure building nozzle in which the pressure of the liquid is built up to a value exceeding the original pressure of the expansible fluid.

The theory of operation of the subject pump is distinctive from that of the usual injector action, in which energy transfer is by impact, with consequent reconversion of most of the original kinetic energy back into heat, implying the necessity of almost complete condensation. In the subject invention a mass of liquid is interposed as a free piston in closing relation to an expansible fluid chamber into which expansible fluid is admitted, causing a build up of fluid pressure until the inertia of the mass of liquid is overcome, whereupon expansion of the fluid against the contiguous face of the liquid mass drives the latter at accelerated velocity toward the pressure building nozzle. Under such conditions of operation the liquid mass absorbs more energy without the consequential shocks incident to action in the combining tube of the usual injector. Since condensation is not essential to the operation, and if present may be small and only incidental, an exhaust port for the expanded fluid is ordinarily provided adjacent the end of the zone of expansion and anterior to the pressure building nozzle. This system permits the handling of hot water such as from a feed water heater.

Another object of the invention is to provide a pump of the type described, in which a feed column of liquid and a flow of expansible fluid are brought into mutual interfering relationship whereby successive masses of liquid are separated from said column by the alternate low pressure phases in said expansible fluid flow occurring between high pressure phases in said fluid flow created by the interposition of the separated liquid masses in occlusive relation in the path of discharge of said expansible fluid.

Other objects of the invention will appear as the following description of several embodiments thereof proceeds.

In the drawings which accompany and form a part of the following specification, and in which, throughout the several figures the same refer-

ence numerals have been used to denote identical parts:

Figure 1 is a longitudinal sectional view of simple apparatus embodying the principles of the invention;

Figures 2 and 3 are diagrammatic views in section, of other forms of apparatus, introduced largely for the purpose of interpreting the scope of the invention.

In the following description, for the sake of graphicness, steam will be used as an example of the expansible pumping medium, and water as the liquid pumped.

Referring now to Figure 1, the pump comprises a body 1, having a water inlet 2, to be connected to a conduit, not shown, conducting a column of feed water to the pump, and a water outlet 3, designed to deliver water at a higher pressure than that of the pumping medium.

Beneath the water inlet 2 is a steam chamber 4, which communicates with the barrel 5. This, as shown, has the tapered form of the combining tube of a conventional injector. This shape is given solely in deference to the fact that there will be some steam condensation as the steam expands, and as a consequent factor of efficiency. However, since in this invention the barrel is not a combining tube and the condensation of steam not essential to its operation, the barrel need not be tapered. For example, if air were the expanding fluid, a straight barrel would be used.

Below the mouth of the barrel 5 and in axial alignment therewith is the convergent end of the pressure building nozzle 6, with a space 7 intervening, for the escape of exhaust steam.

The barrel and the anterior end of the pressure building nozzle are surrounded by a jacket 8, defining an encompassing water chamber 9, having a lateral outlet adjacent the discharge end of the barrel 5 for water and exhaust steam. The barrel 5 may have spillways 11', opening into the water chamber 9, to facilitate displacement of water from the barrel for starting. In normal operation, the inertia of the water in the chamber 9 keeps the water discharging from the barrel flowing into the pressure building nozzle.

Since the intermittent operation in this pump is quite rapid, the following description of its operation may be considered a slow motion narration of what occurs.

Assuming that a slug of water 11 has fallen from the advance end of the water column at the water inlet 2 across the steam chamber 4 during the low pressure phase in said steam chamber, and momentarily occupies the position shown

closing the barrel 5, and that steam is being admitted to the chamber 4, pressure builds up in the chamber 4 until the inertia of the slug 11 is overcome. This pressure reacts also against the lower end of the column in the water inlet 2, but since the mass of said column is greater than that of the slug 11, the effect on said column is only to push it back until the check valve 12 which supports the lower end of said column, closes. As the inertia of the slug 11 is overcome, the steam in the chamber 4 expands, driving the slug 11 through the barrel 5 with accelerated velocity until it reaches the discharge end of the barrel, at which point the exhaust steam escapes through the space 7 and outlet 10 and the slug of water traveling at high speed, enters the pressure building nozzle 22.

When the pressure in chamber 4 is relieved by the discharge of the slug 11, the weight of the feed water column above the water inlet 2 opens the check valve 12 and another slug of water is deposited in the upper end of the barrel 5. It is the successive build up of steam in the chamber 4 that determines the separation of successive slugs of water from the feed water column, and it is obvious that the provision of the check valve 12 is not essential, for the feed water column may be held back whenever the pressure in the chamber 4 rises to a value in excess of the head pressure of said feed water column.

It is apparent also that the admission of steam to the chamber 4 may be continuous, provided it is admitted at such a rate as to give time for pressure build up in said chamber.

In Figure 1, which must be considered quite a specific embodiment of the invention, means is provided for admitting uniform volumes of steam at a uniform head pressure. Such means is per se old in other relations.

The body 1 of the pump is formed with a steam ante-chamber 13, to which steam is admitted through a restricted orifice 14. Communication between the steam ante-chamber 13 and the steam chamber 4 is controlled by a loaded valve 15, which opens when the desired pressure head has built up in the ante-chamber 13. The valve 15 has a greater area when open than when closed, so that it does not instantly close, but remains open until the pressure in the ante-chamber 13 has been appreciably reduced below opening pressure. Since it takes a short time interval for the steam admitted by the valve 15, regardless of its head pressure, to fill the chamber 4 and build up the working pressure therein, there will be alternate low and high pressure phases in the chamber 4, essential to the operation of the pump. It is to be understood that the valve which admits the expansive fluid may cut off the supply of expansive fluid at any predetermined position of the mass of fluid in barrel 5, the degree of expansion being under control of the designer of the apparatus.

Figures 2 and 3 show diagrammatically, simplified embodiments of the invention, in which the employment of valves is dispensed with.

The only difference between these figures is that in Figure 2 the barrel 16 extends transversely with respect to the feed water column 17, while in Figure 3 the barrel 16 and feed water column 17 are in longitudinal alignment. In both cases, the steam is admitted continuously to a steam chamber 18, with which both the feed water column and barrel communicates, the steam being admitted through a restricted orifice 19.

Before the water has fallen into the path of

the steam, the discharge of steam through the barrel is unimpeded and relatively little pressure is developed in the steam chamber. This permits the feed water column in both cases to move into the steam chamber into closing relation to the barrel 16. This immediately obstructs the steam discharge, causing a build up of pressure in the steam chamber which holds back the portion of the feed water column beyond the steam chamber, followed by expansion which drives that portion of the water column constituting the slug 21 which obstructs the barrel, through said barrel with accelerated velocity until the steam exhaust port 20 is reached, whereupon the slug enters the pressure building nozzle 22.

Upon pressure within the steam chamber 18 being relieved by expansion of the steam and displacement of the slug, the feed water column again interposes its frontal portion into closing relation to the barrel 16.

While I have in the above description disclosed several embodiments of the invention, it will be understood to those skilled in the art that these are but a few examples of many alternative forms in which the inventive concept may be expressed.

What I claim as my invention is:

1. Projectile jet pump comprising a barrel having a discharge end and means for admitting expandible fluid to said barrel at a point remote from said discharge end, said barrel having a pressure building nozzle adjacent its discharge end and an exhaust expandible fluid vent anterior to said pressure building nozzle, means for depositing a slug of liquid in said barrel in closing relation thereto adjacent the point of expandible fluid admission whereby expansion of said fluid against said slug drives it through said barrel with accelerated velocity to the point of location of said exhaust vent.

2. Projectile jet pump comprising a barrel having a discharge end and a chamber for expandible fluid remote from said discharge end, means for admitting expandible fluid to said chamber, said barrel having a pressure building nozzle adjacent its discharge end and an exhaust expandible fluid vent anterior to said pressure building nozzle, a conduit for conducting a column of liquid to said expandible fluid chamber positioned to deposit a slug of liquid from the advance end of said column into the adjacent end of said barrel in closing relation thereto adjacent the point of expandible fluid admission, the mass of said slug being less than the mass of said column in said conduit, said column and said slug constituting yielding walls of said expandible fluid chamber, whereby pressure of the obstructed expandible fluid is first built up until the inertia of the slug is overcome, followed by expansion of the expandible fluid against said slug, driving the latter through said barrel with accelerated velocity up to the point of location of said exhaust vent.

3. Projectile jet pump comprising a barrel having a pressure building nozzle adjacent its discharge end, an expandible fluid exhaust vent anterior to said pressure building nozzle, a chamber for building up expandible fluid pressure remote from said exhaust vent and means for admitting expandible fluid to said chamber, a conduit communicating with said chamber positioned to direct a progressively moving column of liquid across a body of kinetic expandible fluid in said chamber from which column portions of liquid are intermittently fed in obstructive relation to the adjacent end of said barrel, each

portion creating a build up of expansible fluid in said chamber which separates said portion from said column followed by expansion of said expansible fluid driving the separated portion with accelerated velocity through said barrel to the point of location of said exhaust vent, the alternate relief of pressure in said chamber incident to the expansion phases of said expansible fluid permitting intermittent feeding of successive portions thereof into obstructive relation to said barrel.

4. Projectile jet pump comprising a barrel having a pressure building nozzle adjacent its discharge end, an exhaust expansible fluid vent anterior to said pressure building nozzle, a chamber for building up expansible fluid pressure, remote from said exhaust vent, a conduit communicating with said chamber positioned to direct a progressively moving column of liquid across a body of kinetic expansible fluid in said chamber from which column slugs of liquid are intermittently fed in obstructive relation to said barrel, means for admitting uniform volumes of expansible fluid at uniform head pressure intermittently to said expansible fluid chamber, comprising an ante-chamber to which expansible fluid is admitted through a restricted orifice, a valve controlling communication between said ante-chamber and expansible fluid chamber, loaded to open when the desired head pressure has been realized in said ante-chamber for admitting kinetic expansible fluid to said expansible fluid chamber, building pressure against said slug until its inertia is overcome, at the same time holding the rest of the liquid column back from said expansible fluid chamber, followed by expansion of the expansible fluid, driving said slug through said barrel with accelerated velocity to the point of location of said exhaust vent, at the same time permitting the advance end of said liquid column to enter said expansible fluid chamber.

5. A pump comprising a barrel having a discharge end, means for admitting elastic fluid under pressure at a restricted rate to said barrel at a location remote from its discharge end, means for providing a slug of liquid in said barrel to close off free elastic fluid flow through the barrel, the first named means causing the elastic fluid to enter the barrel at a low rate with avoidance of jet action upon said liquid which might tend to disperse the liquid, so that the liquid travels through the barrel in the form of a slug accelerated by pressure of expanding elastic fluid, and a pressure building nozzle arranged in axial alignment with the barrel to receive the liquid slug at high velocity and to decelerate it to transform its kinetic energy into pressure.

6. A pump comprising a barrel having a discharge end, a chamber in communication with the

barrel remote from its discharge end, means for admitting elastic fluid under pressure at a restricted rate to said chamber, means for providing a slug of liquid in said barrel to close off free elastic fluid flow through the barrel from the chamber, the communication between the chamber and the barrel causing the elastic fluid to enter the barrel at a low rate with avoidance of jet action upon said liquid which might tend to disperse the liquid, so that the liquid travels through the barrel in the form of a slug accelerated by pressure of expanding elastic fluid, and a pressure building nozzle arranged in axial alignment with the barrel to receive the liquid slug at high velocity and to decelerate it to transform its kinetic energy into pressure.

7. A pump comprising a barrel having a discharge end, a chamber in communication with the barrel remote from its discharge end, means for admitting elastic fluid under pressure at a restricted rate to said chamber to provide pressure fluctuations therein, means for providing a slug of liquid in said barrel to close off free elastic fluid flow through the barrel from the chamber, the communication between the chamber and the barrel causing the elastic fluid to enter the barrel at a low rate with avoidance of jet action upon said liquid which might tend to disperse the liquid, so that the liquid travels through the barrel in the form of a slug accelerated by pressure of expanding elastic fluid, and a pressure building nozzle arranged in axial alignment with the barrel to receive the liquid slug at high velocity and to decelerate it to transform its kinetic energy into pressure.

8. A pump comprising a barrel having a discharge end, an elastic fluid chamber in free communication with the barrel remote from its discharge end, a second elastic fluid chamber, means for admitting to the second elastic fluid chamber a restricted flow of elastic fluid under pressure, valve means between the two chambers for effecting intermittent flow of elastic fluid from the second mentioned chamber into the first, means for providing a slug of liquid in said barrel to close off free elastic fluid flow through the barrel from the first mentioned chamber, the communication between the first mentioned chamber and the barrel causing the elastic fluid to enter the barrel at a low rate with avoidance of jet action upon said liquid which might tend to disperse the liquid, so that the liquid travels through the barrel in the form of a slug accelerated by pressure of expanding elastic fluid, and a pressure building nozzle arranged in axial alignment with the barrel to receive the liquid slug at high velocity and to decelerate it to transform its kinetic energy into pressure.

WALTER H. TINKER.
